UNITED STATES PATENT OFFICE.

FRANCIS X. MALOCSAY, OF UPPER SADDLE RIVER, NEW JERSEY, ASSIGNOR TO INTERNATIONAL BANDING MACHINE COMPANY, A CORPORATION OF NEW YORK.

AUTOMATIC FEEDING MECHANISM.

Application filed May 21, 1923. Serial No. 640,465.

This invention relates to automatic feeding mechanisms adapted to be used in machines which feed a plurality of articles one at a time to feeding positions preparatory to further operations thereon in various other parts of the machine to which they may be transferred manually or automatically. More particularly this invention relates to cigar feeding means adapted to feed a plurality of cigars one at a time to feeding position preparatory to being transferred by automatic means to banding position for operation thereon by a banding machine.

One of the objects of this invention is to provide means which will automatically and efficiently feed cigars to the feeding position more accurately and with greater speed and certainty than is possible by hand or by the present type of machine.

It is a further object of my invention to provide suitable gaging means in conjunction with the feeding means to ensure proper alinement of the cigars in feeding position.

It is a further object of this invention to provide means which will ensure engagement of the gaging means with the next cigar to be moved to feeding position and to ensure movement of a cigar to full feeding position without possibility of lag, which would mean displacement from the proper feeding position.

It is a further object of this invention to provide means for moving a plurality of cigars to feeding position in the same relative order which said cigars occupied while packed in the cigar box, without twisting or in any other manner disarranging or displacing said cigars from their relative position.

Other objects and advantages will appear as the nature of the improvements is better understood, the invention consisting substantially in the novel arrangement and correlation of instrumentalities herein fully described and illustrated in the accompanying drawings considered together or separately and then finally pointed out and specifically defined and indicated in the appended claims.

The disclosure made the basis of exemplifying the present inventive concept suggests a practical embodiment thereof, but the invention is not to be restricted to the exact details of this disclosure, and the latter, therefore, is to be understood from an

illustrative, rather than a restrictive, standpoint.

The inventive idea involved is capable of receiving a variety of mechanical expressions, one of which, for the purposes of illustration, is shown in the accompanying drawings, in which—

Fig. 1 is a front elevation of a machine embodying my invention, parts of the machine being broken away, and other parts not necessary to a description of my invention having been removed; and

Fig. 2 is a plan view of the device shown in Fig. 1 but with the top plate removed to uncover the underlying structure.

Referring to the drawings, a layer of cigars 1 is adapted to be discharged from a hopper upon a table 2 in such manner that the cigars occupy the same relative positions as in the cigar box when packed.

The feeding mechanism comprises two or more bars 3 which are given an up-and-down movement, compounded with a left-to-right movement. The movement is therefore essentially elliptic. The bars are free to operate through longitudinal slots cut in the table top. In their upward and right movement, the bars are raised above table 2 to lift the row of cigars off the table and move them to the right. In their lower and left movement they deposit the cigars on the table and move beneath the table out of contact with the cigars.

Each bar 3 is provided with a plurality of downwardly extending forks 30 adapted to straddle a shaft 5 at one end of an arm 6 of bell crank 7 pivoted in a hanger 8 fixed to the main fixed frame of the machine. Also pivoted on the axis of the shaft 5 is a gage finger 9 adapted in its extreme movement to the right to gage the cigar in feeding position.

A plurality of gage fingers 9 are shown (see Fig. 2), and in the following description it will be understood that whenever "gage finger" is mentioned, a plurality of fingers may be implied. The gage finger 9 is also given an up-and-down movement, compounded with a right-to-left movement. The gage finger is caused to lag somewhat behind the downward movement of the bars (by mechanism to be hereinafter described) to hold the first cigar in feeding position, to be operated upon while in said position, or until said cigar can be gripped by mecha-

nism (not shown) adapted to transfer it to a second or banding position. Then the gage finger is lowered out of contact with the cigar in feeding position, and the left movement thereof is substantially the same as that of the bars. For the purpose of giving the bars their up-and-down movement, there are provided bell cranks 12, pivoted on the fixed frame at 43, having rollers 42 at the end of one arm and having their other arms connected by link 13 to effect parallel movement of the bell cranks. The bars 3 are each provided with a downwardly extending rib 30^a adapted to enter the space between the flanges of rollers 42 for guiding said bars. The bell cranks are rotated by a link 14 connected to the pivot of one of them (here shown as the left bell crank), the said link being connected to a link 15 attached at 96 to bell crank 16 pivoted at 17 on the main frame of the machine and operated from the cam 19 at the extreme right engaging a roller 20 at the end of arm 21 of said bell crank. The forward and rearward movement of said bars, which is compounded with the up-and-down movement, is effected by means of the bell crank 7, one arm 6 of which engages in the forks 30 on the underside of the bars, said bell crank 7 having a roller 25 in engagement with a cam 26 carried by a hub 27 fixed to the extreme left end of an operating shaft 29 to be reciprocated therewith. During the movement of the cam to the right, the bars 3 drop below the table through the cam 19 and its connecting mechanism. The cam eventually moves so far to the right that gage finger 9 engages the row of cigars on the table which have sufficient resistance to prevent further downward rotation of the bell crank 7. The roller 25 may at this time be some distance off cam 26. By this arrangement, therefore, it is assured that the gage finger 9 will, in every case, come into contact with the next cigar to be moved to feeding position. The degree of movement of the gage finger to the left is such that said finger engages the row of cigars and moves said row slightly to the left before it reaches the limit of its left movement. During the movement of cam 26 to the left, bell crank 7 is rotated to move the bars 3 and finger 9 to the right. Not only the bars, therefore, but the finger 9 gets its right and left movement from cam 26 operated by the main shaft 29. Finger 9, however, is only pivotally connected to one arm of bell crank 7 and is given a separate, independent up-and-down movement, so that when the bars go down to deposit the cigars on the table top 2, the gage finger 9 still remains upward until some gripping member is caused to engage the cigar in feeding position. The gage finger 9 is then drawn downwardly to disengage said first cigar and is moved rearwardly by

bell crank 7 together with bars 3, and is later moved upwardly to engage the second cigar after having been drawn back somewhat less than one cigar width. The movement to the left continues so that gage 9 probably moves the row of cigars to the left a trifle as described, thus ensuring engagement with the next cigar. The movement to the right is then accomplished as before by the bell crank 7, the bars being in elevated position through the operation of links 14, 15. To give the gage finger 9 a separate up and down movement, there is pivoted thereto at 45, intermediate the length thereof, a link 32, whose other end has a universal connection 33, to a hub 34 which is operated by bell crank 35 in engagement with cam 36 on the main driving shaft 40.

Shaft 29 may be fixed at its right end in a hub 47 having rollers 46 whereby said shaft and the mechanism carried thereby are supported upon rails 48 on the main frame of the machine.

The reciprocation of cam 26 may be accomplished by connecting to the main shaft 29 a link 60 having its other end pivotally connected to a lever 50, pivoted at 51 at the rear of the machine, said lever being adapted to be operated by a cam 52, mounted upon a shaft 53. The cam 19 which effects the up-and-down movement of bars 3 may be mounted upon the same shaft 53 as cam 52. Shaft 53 may be suitably geared to shaft 40 and the latter driven from any suitable source of power, such as a motor, either directly or through belts and pulleys, and by suitably positioning and shaping the cams 19, 36 and 52, the correct timing may be obtained. That is to say, cam 19 will be so positioned relative to cam 52 that every time the bars 3 move toward the right, they will also be elevated, and every time they move toward the left they will be depressed. The cam 36 is so positioned that finger 9 will be depressed a certain predetermined length of time after bars 3 and will be elevated slightly in advance or substantially simultaneously with said bars.

The operation of the feeding mechanism, although apparent from the foregoing description, may be described as follows:

Assume the parts to be as shown in Fig. 1. A cigar has been deposited in feeding position and the bars 3 are moving downwardly. A predetermined time thereafter, finger 9 begins to move downwardly until it is below the table top. The bars and finger 9 now move beneath the table to the left and as they approach the limit of their movement toward the left, the bars and finger are elevated, the finger 9 coming up a short distance in front of the next cigar to be fed to feeding position. The finger, therefore, comes up before the bars and finger have moved the width of one cigar toward the

left and the upward movement of the finger may be somewhat in advance of the bars. The total stroke to the left somewhat exceeds one cigar width, as hereinbefore described, to ensure the engagement of the finger with the row of cigars. The bars are then moved upwardly to lift the row of cigars out of engagement with the table, the finger having previously been raised, and are moved to the right to feeding position. The bars then move downwardly to deposit the cigars, as shown in Fig. 1, and the operation is repeated. Since the cams are rotated continuously, this feeding operation will also be continuous and automatic.

Suitable springs 70, 71, 72 may be provided for holding bell cranks 7 and 16 and link 50 in effective engagement with their respective cams.

Throughout this specification I have described my invention in connection with a cigar feeding and banding mechanism, but I wish it distinctly understood that this was solely for illustrative purposes and to describe one practical embodiment of my invention, and that the invention herein is capable of a wide variety of uses on other articles. Thus, for example, the device can be utilized in connection with candy wrapping or banding machinery or generally with any type of wrapping or banding machine wherein a plurality of similar articles are fed to a banding or wrapping machine and then discharged.

The subject matter of this application is disclosed in my co-pending application, Serial No. 640,463, filed May 21, 1923.

In accordance with the provisions of the patent statute, I have described the principle of my invention together with the apparatus which I now consider to represent a practical embodiment thereof, but I desire it understood that my invention is not confined to the particular form of apparatus herein shown and described, the same being merely illustrative, and that the invention can be carried out in other ways without departing from the spirit of my invention, and, therefore, I claim broadly the right to employ all equivalent instrumentalities coming within the scope of the appended claims, and by means of which objects of my invention are attained, and the new results accomplished, as herein set forth, as it is obvious that the particular embodiments herein shown and described are only some of many that can be employed to attain these objects and accomplish these results.

Having described my invention, what I claim and desire to secure by Letters Patent is:

1. In a device of the character described, means for feeding a row of articles one at a time to feeding position, comprising feeding members and a gage member, and means

for imparting a substantially elliptic movement to said members.

2. In a device of the character described, means for feeding a row of articles one at a time to feeding position, comprising feeding members and a gage member, and means for imparting a combined vertical and horizontal reciprocatory movement thereto.

3. In a device of the character described, means for feeding a row of articles one at a time to feeding position, comprising feeding members and a gage member, means for reciprocating said members toward and away from feeding position, and means for reciprocating said members vertically.

4. In a device of the character described, means for feeding a row of articles one at a time to feeding position, comprising feeding members and a gage member, means for reciprocating said members toward and away from feeding position, and means for simultaneously reciprocating said members vertically.

5. In a device of the character described, means for feeding articles to feeding position comprising a feed member and a gage member, a single means for reciprocating said members toward and away from feeding position, and individual means for reciprocating said members vertically.

6. In a device of the character described, a supporting surface, means for feeding articles to feeding position comprising a feed member and a gage member, means for reciprocating said members toward and away from feeding position, and means for raising said members above said surface when moving toward feeding position and for lowering said members below said surface when moving away from feeding position.

7. In a device of the character described, a supporting surface, means for feeding articles to feeding position comprising a feed member and a gage member, means for reciprocating said members toward and away from feeding position, means for raising said members above said surface when moving toward feeding position and for lowering said members below said surface when moving away from feeding position, and means for causing said gage member to lag behind said feed member in the downward movement.

8. In a device of the character described, means for feeding articles to feeding position, means for gaging said articles in feeding position, a common means for reciprocating said first two means toward and away from feeding position, and means for simultaneously reciprocating said first named means vertically.

9. In a device of the character described, means for feeding articles to feeding position, means for gaging said articles in feed-

ing position, a common means for reciprocating said first two means toward and away from feeding position, and independent means for each of said first two means for simultaneously reciprocating said first two means.

10. In a device of the character described, a supporting surface for a plurality of articles, a feed member and a gage member adapted to operate through said surface, and means for imparting a substantially elliptic movement to said members to raise said members above said surface when moving toward feeding position and lower said members below said surface when moving away from feeding position, said gage member being adapted to engage said articles near the end of its movement away from feeding position.
11. In a device of the character described, a supporting surface, means for feeding articles to feeding position comprising a feed member and a gage member, means for reciprocating said members toward and away from feeding position, means for rais-

ing said members above said surface when moving toward feeding position and for lowering said members below said surface when moving away from feeding position, and means for causing said gage member to lag behind said feed member in the downward movement and for causing said gage member to be raised in advance of said feed member.

12. In a device of the character described, means for feeding an article to a predetermined position comprising feeding members and a gage member, and means for imparting a substantially elliptic movement to said members.

13. In a device of the character described, means for feeding an article to a predetermined position comprising feeding members and a gage member, and means for imparting a combined vertical and horizontal reciprocatory movement thereto.

This specification signed this 7th day of May, 1923.

FRANCIS X. MALOCSAY.
